UNITED STATES PATENT OFFICE.

JOHN E. ROTHWELL, OF BOULDER, COLORADO, ASSIGNOR OF TWO-THIRDS
TO THE STEARNS-ROGER MANUFACTURING COMPANY, OF DENVER,
COLORADO.

COOLING ATTACHMENT FOR ORE-ROASTING FURNACES.

SPECIFICATION forming part of Letters Patent No. 625,608, dated May 23, 1899.

Application filed May 18, 1897. Serial No. 637,027. (No model.)

To all whom it may concern:

Be it known that I, JOHN E. ROTHWELL, a subject of the Queen of Great Britain, residing at Boulder, in the county of Boulder and State 5 of Colorado, have invented a certain new and useful Improvement in Cooling Attachments for Ore-Roasting Furnaces, of which the following is a full, clear, and exact description.

The object of this invention is to provide 10 means for cooling the hot ore as it is discharged from roasting, drying, calcining, and other furnaces or apparatus on its way from the furnace to a place or apparatus for further treatment, it being desirable to cool the 15 ore in order to facilitate its handling.

There is in use at this time what is known as the "Pearce" turret-furnace, (see Patents No. 488,797, dated December 27, 1892, and No. 506,129, dated October 3, 1893;) and my invention 20 has been designed, primarily, as an attachment for that furnace in order to effect the cooling of the hot ore, so that the roasted ore may be more readily and harmlessly handled in the subsequent treatment thereof.

25 The invention comprises a casing or shell adapted to contain water or other cooling agent and provided with through-tubes for the passage of the ore through the cooling atmosphere, as I will proceed now more particularly to set forth and finally claim.

In the accompanying drawings, illustrating 30 my invention, in the several figures of which like parts are similarly designated, Figure 1 is a top plan view of one form of cooling attachment constructed in accordance with my invention. Fig. 2 is a vertical section taken in the plane of lines 2 2, Fig. 1. Fig. 3 is an end elevation. Fig. 4 is a horizontal section of portion of a Pearce turret-furnace with my 35 invention applied, and Fig. 5 is a vertical section.

As at present planned the cooling device 40 comprises a casing or shell *a*, containing transverse or vertical tubes *b*, open at both ends, through which the hot ore descends, a stream 45 of flowing water or other cooling agent, preferably under pressure, passing through the casing and about its tubes and serving to effect the cooling of the ore in its passage 50 through the tubes.

c is the intake, and *d* the outflow, for the cooling agent.

The tubes *b'* may have their lower ends simply spread in the bottom sheet *a'* of the shell or casing, while their upper ends *b''* may 55 be spread and headed in the crown or upper sheet *a''* of the casing; but I do not limit my invention to the manner of securing the tubes in the shell or casing.

The shape of the device may, and prefer- 60 ably will, conform to the hearth of the furnace, that shown being a segment of the hearth of the Pearce turret-furnace.

The attachment may be built into the fur- 65 nace—as, for example, upon the beams *e e*, which are set into the brickwork and from which the attachment is suspended by its brackets *f*.

g g are hand-holes for access to the casing 70 for cleaning purposes.

The attachment is arranged at the discharge 75 end of the hearth and with its entrance end substantially on a level with the floor of the hearth, and the roasted ore is discharged from the hearth into the attachment by the rakes or stirrers or equivalent mechanism of the furnace and, falling slowly through the tubes of the attachment, is cooled. The cooled ore may fall thence upon a feeding device, whence or by which it is taken to a conveyer or ele- 80 vator for further treatment. The flowing water insures a cooling atmosphere or agency in the attachment.

Although I have shown cylindrical tubes, I 85 do not limit my invention thereto. Neither is the invention limited to the form of attachment shown. The gist of the invention is a tubular cooling attachment for ore roasting, drying, or calcining furnaces, arranged with its entrance substantially on a level with the 90 floor of the hearth of the furnace, to which the hot ore may be fed and from which the cooled ore may be removed in and by any appropriate automatic, gravity, or other means.

As already sufficiently indicated, the cool- 95 ing attachment may be a section of the hearth in plan, or it may be of other appropriate form to adapt it for economical application to the furnace or apparatus with which it is to be used, and it may be arranged in the 100

hearth of the furnace or apparatus or outside of the same.

In Figs. 4 and 5 I have shown my invention as applied to the Pearce turret-furnace, 5 and in said views the parts shown and not described are common in the present construction of said furnace and form no part of the present invention, and, as already stated, the invention is applicable to other than that 10 furnace.

What I claim is—

The combination with an ore-roasting furnace, the flat hearth thereof and means to discharge the ore from such hearth, of the 15 herein-described ore-cooling attachment, arranged at the discharge end of such hearth

and with its entrance substantially level with the floor of the hearth, and comprising the shell or casing *a* containing a series of tubes which open at both ends outside of said shell 20 and through which tubes the ore passes by gravity as it is fed thereto, and means to circulate the cooling agent, such as water, through such shell or casing and around the said tubes, substantially as set forth. 25

In testimony whereof I have hereunto set my hand this 15th day of May, A. D. 1897.

JOHN E. ROTHWELL.
